(57) **CLAIM**

The ornamental design for a front fairing, as shown and described.

DESCRIPTION

FIG. 1 is a perspective view taken from a front, left side of a front fairing according to a first embodiment of our design;

FIG. 2 is a front elevation view thereof;

FIG. 3 is a rear elevation view thereof;

FIG. 4 is a left side elevation view thereof;

FIG. 5 is a top plan view thereof;

FIG. 6 is a bottom plan view thereof;

FIG. 7 is a perspective view taken from a front, left side of a front fairing of FIG. 1 shown on a personal watercraft shown in dotted lines;

FIG. 8 is a perspective view taken from a rear, left side of a front fairing of FIG. 1 shown on a personal watercraft shown in dotted lines;

FIG. 9 is a perspective view taken from a front, right side of a front fairing according to a second embodiment of our design;

FIG. 10 is a front elevation view thereof;

FIG. 11 is a rear elevation view thereof;

FIG. 12 is a right side elevation view thereof;

FIG. 13 is a top plan view thereof;

FIG. 14 is a bottom plan view thereof;

FIG. 15 is a perspective view taken from a front, right side of a front fairing of FIG. 9 shown on a personal watercraft shown in dotted lines; and,

FIG. 16 is a perspective view taken from a rear, right side of a front fairing of FIG. 9 shown on a personal watercraft shown in dotted lines.

Throughout the Figures, where shown: (i) the elements of the front fairing shown in dotted lines are for illustrative purposes only and do not form part of the claimed design; and (ii) in FIGS. 1 to 4, 6, 7 and 8, and FIGS. 9 to 12, 14, 15 and 16, the dotted/dashed lines represent unclaimed boundaries of the claimed design and as such, the configuration of the unshaded surfaces defined by dotted/dashed lines immediately adjacent solid lines form no part of the claimed design. In FIGS. 7, 8, 15, and 16, the personal watercraft shown in dotted lines is shown for illustrative purposes only and do not form part of the claimed design. Portions of the front fairing not shown in the Figures and not otherwise described in this Specification do not form part of the claimed design.
